UNITED STATES PATENT OFFICE

MERLE P. CHAPLIN, OF WATERVILLE, MAINE, ASSIGNOR, BY MESNE ASSIGNMENTS, TO FIDELITY TRUST COMPANY, OF PORTLAND, MAINE, A CORPORATION OF MAINE, AS TRUSTEE

DESIGN FOR A MOLDED FIBER PLATE

Application filed November 30, 1929. Serial No. 33,589. Term of patent 14 years.

To all whom it may concern:

Be it known that I, MERLE P. CHAPLIN, a citizen of the United States, residing at Waterville, in the county of Kennebec and State of Maine, have invented a new, original, and ornamental Design for a Molded Fiber Plate, of which the following is a specification, reference being had to the accompanying drawings, forming part thereof.

Fig. 1 is a plan view of the plate.

Fig. 2 is an end elevation of the same, one-half being in section taken on the line 2—2, Fig. 1, and

Fig. 3 is a fragmentary sectional plan of the plate taken on line 3—3, Fig. 2.

The design consists in the novel configuration imparted to the plate. The plate presents a plane bottom portion, an angular side wall and a horizontal rim or border. The

rim or border presents spaced straight edge portions disposed symmetrically about the plate and spaced from each other by the rounded corner portions. The effect produced by this configuration is carried out in the plate bottom as well as in the side wall and enclosing rim or border by extending the plate bottom outwardly at the corners of the plate. The extensions are disposed in the plane of the plate bottom proper and appear as recesses included between side wall and rim, the spaces between said recesses extending as relatively straight edges disposed inwardly from the relatively straight edges of the rim and substantially parallel thereto.

I claim:

The ornamental design for a molded fiber plate, as shown and described.

MERLE P. CHAPLIN.
